UNITED STATES PATENT OFFICE.

CHARLES B. KIRKHAM, OF BUFFALO, NEW YORK, ASSIGNOR TO CURTISS AEROPLANE
AND MOTOR CORPORATION, A CORPORATION OF NEW YORK.

AIR-HEATER FOR AERONAUTICAL MOTORS.

1,326,405.

Specification of Letters Patent.

Patented Dec. 30, 1919.

Application filed September 27, 1916. Serial No. 122,437.

To all whom it may concern:

Be it known that I, CHARLES B. KIRKHAM, a citizen of the United States, residing at Buffalo, in the county of Erie and State of 5 New York, have invented certain new and useful Improvements in Air-Heaters for Aeronautical Motors, of which the following is a specification.

My invention relates to internal combustion engines and has special reference to an 10 improved substantially streamline form of heater intended for use upon aeronautical motors of the multi-cylinder type.

For continuous operation of an aeronautical motor at high speed, especially during 15 the winter months when the surrounding air is at a very low temperature and at high altitudes, it is essential that the continuity of the fuel supply to the engine cylinders 20 be uninterrupted so long as the air craft is in flight. Condensation of the fuel gases under the conditions specified, if a preventive is not installed, is responsible more than anything else for motor stoppage and 25 the danger resulting therefrom to both the aviator and the machine. Continuous motor operation is best obtained by the admission of preheated air to the carburetion system and it is to this end, *i. e.*, the production 30 of an essentially novel, substantially streamline air heater that the present invention is designed.

In practice, I contemplate the utilization 35 of two heater jackets of a construction intended for positive and coöperative association with the several horizontally alined exhaust conduits characteristic of the "Curtiss" V-type motor. By the provision of a separate heater for the exhaust conduits of 40 each bank of engine cylinders, it is possible to maintain perfect symmetry (essential to aircraft construction) and at the same time provide for the ample supply of preheated air to the motor carbureters, of which, in 45 the present instance, there are two—one for each bank of cylinders. To amplify the air supply to the dual carbureter system and to insure a positive induction of air at a speed forced by the air rush incident to 50 flight, it is proposed to provide an opening in and at the forward end of each heater jacket. The several exhaust conduits pierce the heater jackets in alined relation and to a certain extent break or deflect the air rush

to accordingly augment the heating influence offered upon the air prior to its admission to the carbureters. The aft end of each heater jacket is closed in conical form and the air confined to the opposed jackets thus caused to seek an outlet provided therefor—open to the carburetion system. Various details of construction are also considered novel and will be therefore specifically disclosed hereinafter.

For a detailed description of the invention, reference should be had to the accompanying drawings wherein like characters of reference designate like or corresponding parts throughout the several views, of 65 which:

Figure 1 is a fragmentary side elevation of a tractor aeroplane equipped with a Curtiss V-type motor that the application of the invention may be advantageously 70 shown;

Fig. 2 is a front end elevation of the aeroplane and equipment illustrated in Fig. 1, and

Fig. 3 is an enlarged transverse section of the heated jacket illustrating the manner 80 in which the exhaust conduits pass therethrough.

In the embodiment of the invention selected for illustration, 10 designates the forward end of the fuselage or body portion 85 of a tractor aeroplane equipped with a standard Curtiss V-type aeronautical motor. The cylinders of the motor are designated 11 and arranged in banks at opposite sides of the fore and aft axis of the machine, 90 each cylinder extending without the fuselage or body portion 10.

The exhaust conduits 12 lead from the exhaust ports of the motor in series, the conduits of each series extending in horizontally alined relation. In an eight-cylinder motor of the type illustrated, there are four exhaust conduits located at each side of the machine.

It is customary at the present time to 100 equip a multi-cylinder V-type motor with a dual carbureter system that the fuel supply to the several cylinders may be ample and continuous. The carbureter system herein illustrated is designated in its entirety by 105 the numeral 13. The provision of the dual carbureter system 13 makes it advantageous to provide a dual air heater system, not only

to gain symmetry but to provide for the ample induction of heated air to the engine cylinders.

Each series of conduits 12 acts as a support for its associated heater jacket 14, the heater jacket, in each instance, having a greater diameter than the diameter of the conduits 12. As illustrated to advantage in Fig. 1, the several conduits pierce or penetrate the jackets 14 to terminate therebeyond, and, being of smaller diameter, afford an air passage way interiorly of the heater jacket above and below the conduits piercing therethrough. In view of such an arrangement, the air flow interiorly of each heater jacket is somewhat baffled and appreciably broken to accordingly augment the resulting heating influence thereon.

In form, each heater jacket or grid is of a substantially streamline formation having a frusto-conical forward terminal 15 and a truly conical aft terminal 16. An opening 17 is formed in each heater jacket at its forward end to insure a forced induction of air proportionate to the air rush incident to flight. Such an arrangement is conducive to the maximum air supply during flight at high speed and a relatively decreased supply as the speed of the machine is reduced. The aft end of each jacket being closed, the air confined therein is caused to seek an outlet which, for reasons hereinafter explained, I locate adjacent the rear end of the jacket, preferably equidistant from the rear spaced conduits 12. An outlet pipe extension 18 is formed upon the heater jacket at each side of the motor for fitting engagement with one end of an associate flexible carbureter air supply pipe 19, of which in the embodiment shown, there are two, located respectively at opposite sides of the fuselage to extend thereinto at a point in proximity to each heater jacket and as illustrated in Fig. 2. By thus inclosing the carbureter air supply pipes 19, the head resistance during flight is appreciably reduced.

The substantially streamline formation of each heater jacket will further serve to reduce the head resistance by reason of the fact that the major portion of each exhaust conduit is embraced or inclosed by one or the other of the streamlined jackets and accordingly given a substantially streamline form. Each conduit 12 extends but a little beyond its inclosing jacket,—i. e., only sufficient to conduct the spent gases to the open atmosphere. To preclude the formation of a retarding force, the conduits are each of a special end formation, preferably beveled as indicated at 20 in Fig. 1.

The fastening means for each heater jacket may be described as comprising a clip 21 of a right-angle formation designed for riveted fastening as indicated at 22 to

the heater jacket and bolted fastening as indicated at 23 to the conduit 12. Each jacket 14, at the diametrically opposed openings formed therein through which the conduits 12 extend, is outwardly flanged as indicated at 24, the flange encircling the conduits 12 to offer an increased bearing surface, a snug or tight fit and at the same time a positive centering and alining means.

In use, and during flight, air enters the heater jackets 14 via the forward openings 17 formed therein where it impinges or contacts the exhaust conduits 12. The air thus confined to the jackets 14 is heated by the heat of the exhaust and through the suction force of the carbureter system occasioned by movement of the engine pistons, admitted to the carbureter system for ultimate distribution to the engine cylinders in a pre-heated state. Condensation of the fuel gases in winter, at high altitudes and under all circumstances is thus effectually prevented.

The very compactness of an aeronautical motor while essentially and certainly advantageous in many respects necessarily brings at least one of the valve operating springs into such proximity to the exhaust conduits 12 as to offer thereon a deteriorating effect. The heat from the exhaust during high speed operation of the motor is intense and unless some means be provided whereby the adjacent valve operating springs are protected, the spring metal will eventually soften, decrease in resiliency and finally fail to function in properly controlling operation of its associate valve mechanism. The springs thus affected are herein denoted 25. To obviate the foregoing contingency and to deflect the heat of the exhaust, I interpose between the conduits 12 and the several springs 25 a shield 26 of appropriate design. The shield, as illustrated to advantage in Fig. 3, may be made as an integral part of the conduit 12 or if desired fastened thereto or to the engine cylinder.

While in the foregoing I have illustrated one preferred embodiment of the invention, I desire it to be understood that the exhaust conduits may be set at a rearward inclination, the heater jacket changed in general conformation and the type of shield interchanged should occasion demand. Further, I do not intend that the device of the invention shall be limited in its use to a Curtiss V-type motor, for it is apparent in its inception that the nature of the invention is such as to warrant unrestricted utility and application in connection with motors varying greatly in type. Specifically, I desire to be limited only in so far as the scope of the subjoined claims must warrant.

What is claimed is:

1. In an aircraft, an internal combustion motor having exhaust conduits in bank, an

air heater casing of substantially uniform dimensions throughout and streamlined at its ends, said casing enveloping said conduits and having an ingress opening facing in the 5 direction of travel of the aircraft, and an egress opening connected with the motor, and means for securing said casing to said bank of conduits.

2. The combination with an aircraft, the 10 internal combustion engine therefor and the exhaust conduits of said engine, of a substantially streamline air heater casing partially surrounding said exhaust conduits, said casing being elongated and having a 15 large portion thereof of substantially uniform dimensions throughout, said casing also having an opening facing in the direction of travel of the aircraft and an egress opening connected with the motor, and 20 means securing said air heater case to said conduits.

3. The combination with an internal combustion engine and the exhaust pipes therefor, of a substantially streamlined air heater 25 having an open substantially frusto-conical forward end and a closed substantially conical rear end, and a conduit leading from the heater to the motor.

4. In an aircraft, an internal combustion 30 motor, exhaust conduits therefor which project without the body of the craft, a substantially streamlined air heater jacket of an elongated cylindrical shape incasing said

exhaust conduits and having its extreme forward end open to the atmosphere, and an 35 air conduit connecting the rear end of said casing with the motor, and means securely fastening said cylindrical casing to said exhaust conduit.

5. The combination with an internal combustion motor and the exhaust conduits therefor, of an air heating system comprising an air heating jacket partially surrounding said exhaust conduits, said heater jacket being of an elongated cylindrical shape and 40 having its ends streamlined said jacket also having an opening facing in the direction of travel of the aircraft, and a means to convey heated air from the heater jacket to the cylinders of the engine, and means 45 securely fastening said cylindrical casing to said exhaust conduits.

6. In an air craft, an internal combustion motor, the exhaust conduits therefor, a substantially streamlined air heater jacket 55 of cylindrical shape having rows of longitudinally spaced apertures on opposite sides of said jacket through which said conduits pass, and an integral flange around each of the exhaust conduit apertures to make a tight 60 fit between the conduits and the heater jacket, and means securing said flanges to the exhaust conduits.

In testimony whereof I affix my signature.

CHARLES B. KIRKHAM.
